UNITED STATES PATENT OFFICE.

CHARLES RAYMOND BRADY, OF TORONTO, ONTARIO, CANADA.

MECHANICAL TOY.

Application filed December 30, 1926. Serial No. 157,994.

The invention relates to improvements in mechanical toys as described in the present specification and shown in the accompanying drawings which form part of the same.

The invention has for its object to animate toy figures and objects in simulation of life-like movement by the provision of a fan driven by hot air currents, the toy being placed over a radiator or stove for this purpose. In this manner a toy is produced which causes considerable amusement to children. A variation of toys of this nature may be constructed of a large variety of figures and actions dependent upon the character and motion that it is desired to represent.

Subsidiary objects of the invention are to produce a base by which a toy can be attached to a wall or to a stovepipe so as to permit of its being disposed in the path of hot air currents.

With these objects in view other objects will appear as the description proceeds.

Referring to the drawings, Figure 1 depicts an embodiment of the invention in which a man is illustrated operating a fan wheel. This view is shown partly in section.

Figure 2 is a transverse sectional view taken on the line 2—2 thereof. Figure 3 is a detail partly in section showing the base of the toy fastened to a wall. Figure 4 is a perspective view illustrating the frame and the base attached to the joint of a stovepipe. Figure 5 is a modified form of the invention exhibiting a man and woman sawing a log of wood.

Like numerals of reference indicate corresponding parts in each of the figures throughout the drawings.

Referring more particularly to Figures 1 to 4 inclusive, the reference numeral 10 indicates a rectangular frame of band iron or other material in which is set a male figure comprising a body 11 pivoted at 12 to legs 13, the legs of the man being securely affixed to the base 14 in any manner found convenient. In front of the man is a vertical shaft 15 rotatably mounted in the top piece 16 of the frame 10 and resting at its lower extremity in an indent or centre punch depression 17, the lower extremity of the shaft being sharpened to a point in order to engage in this indent.

The top end of the shaft carries an integral disk 18 upon which is laid a fan 19 having a central disk-like portion 20 which lies con-

tiguous upon the disk 18 and has an aperture to permit the shaft projecting therethrough, the outer portion of the fan being composed of the usual blades or impellers as usual in fan construction.

It will be seen that by this construction the disk portion of the fan frictionally engages the disk of the shaft so as to provide a frictional drive therebetween. This form of connection is very advantageous in that it permits of the fan being taken off the shaft in order to disassemble the toy for packing purposes.

21 is a crank constructed integral with the shaft 15 and attached to a connecting rod 22 which connecting rod constitutes the arms of the man and is pivotally connected to the body 11.

The pivotal connection consists of a stud 23 of such a length as to permit the connecting rod to have the necessary lateral movement occasioned by the throw of the crank as shown in Figure 2. This stud is passed through a fairly large aperture in the body and is headed as at 24. This design provides a very practical and economical construction for producing the desired play in the pivotal connection necessary to permit of the free working of the arm.

The base of the toy comprises a platform 25 consisting of two lengthwise members 25 attached to the bottom piece 14 by a nut and bolt 26. Each extremity of each member 25 is bent downwardly to form legs as at 27 and one end of said members also extends upwardly as at 28 so as to provide a vertical attaching face.

Referring more particularly to Figure 3; when desired to attach the toy to the wall over a radiator or other heating agent, it is merely necessary to screw it to the wall by means of its vertical face composed of the legs 27 with their extensions 28. In the case where it is desired to mount the device over a stove, the legs 27 at one end of the members 25 are inserted between the joint of two adjacent lengths of stovepipe as depicted in Figure 4. To do this the horizontal members 25 are turned on their pivotal bolts 26 so as to converge in order to position their ends 27 in conformity with the rotundity of the stove pipe. It will of course be understood that when the device is placed upon a radiator it will be supported upon all of its legs 27.

In operation the rising currents of air rotate the fan 19, which through its connection operates the shaft 15 and as this shaft is connected to the figure by means of arms 22 5 the backward and forward motion is communicated thereto which simulates the figure in the action of operating a fan wheel.

Referring to the modified form shown in Figure 5, this shows a couple of figures 28 10 and 29 working a cross-cut saw 30 which is freely mounted in a slot in a member 31; which member represents a log of wood. The bodies of the figures are pivotally mounted as described in reference to Figure 15 1 and the arms are pivotally attached to the body of each figure and rigidly attached to the saw. The female figure 29 has a depending lever 32 integral therewith, the lower end of which is pivotally attached to 20 a connecting rod 33 that in turn is attached to a crank 34 of a vertical shaft 35. This shaft is mounted in the frame of the toy in a manner similar to that recounted in detail in the previous embodiment of the invention 25 and has a fan of a similar construction thereto. The base of the frame is made boxlike as at 36 in order to conceal the crank mechanism from view and the lever 32 is also concealed from view by being enclosed between

two plates 37 which constitute the skirt of 30 the female figure.

In operation it will be seen that motion is communicated to the shaft 35 from the fan which reciprocates the connecting rod 33 thus causing oscillation of the lever 32. 35 This oscillation is utilized for the purpose of moving the bodies 28 and 29 backwards and forwards on their pivotal axis in simulation of the figures sawing a log of wood.

What I claim is:—

In a mechanical toy of the class described, a narrow rectangular frame vertically positioned, a shaft likewise positioned, said shaft being journalled in an aperture in the top member of the frame and its lower end being pointed and resting in an indent in the bottom member of the frame, a disk integral with the top end of the shaft, a fan having an apertured disklike centre for resting upon the shaft disk and receiving the tip 50 of the shaft, a crank integral with the shaft, a jointed figure supported within the frame and mechanical connections extending therefrom to the crank of the shaft.

Signed at Toronto, Ontario, this 24th day 55 of December, 1926.

CHARLES RAYMOND BRADY.
